(57) **CLAIM**

We claim, the ornamental design for a device for self-monitoring of heart conditions and vital signs, as shown and described.

DESCRIPTION

FIG. 1 is a perspective view of a device for self-monitoring of heart conditions and vital signs, showing our new design; FIG. 2 is another perspective view thereof; FIG. 3 is another perspective view thereof; FIG. 4 is a back view thereof; FIG. 5 is a right side view thereof; FIG. 6 is a top view thereof; FIG. 7 is a front view thereof; FIG. 8 is a left side view thereof; and, FIG. 9 is a bottom view thereof.

Portions shown in broken lines illustrate environment and form no part of the claimed design.

1 Claim, 9 Drawing Sheets
